CLAIM

The ornamental design for a rake, as shown and described.

DESCRIPTION

FIG. 1 is a side elevational view of a rake showing my new design, the opposite side being a mirror image of that shown;

FIG. 2 is an enlarged perspective view thereof, with the handle portion shown broken-away for ease of illustration; and

FIG. 3. is a further enlarged fragmentary perspective view thereof, taken along line 3—3 of FIG. 2.

FIG. 1

FIG. 2

FIG. 3
